UNITED STATES PATENT OFFICE.

JOHN R. ROGERS, OF BROOKLYN, NEW YORK, ASSIGNOR TO MERGENTHALER LINOTYPE COMPANY, A CORPORATION OF NEW YORK

TYPOGRAPHICAL DISTRIBUTING MACHINE.

Application filed February 5, 1924. Serial No. 690,683.

To all whom it may concern:

Be it known that I, JOHN R. ROGERS, a citizen of the United States, residing at Brooklyn, in the county of Kings and State 5 of New York, have invented certain new and useful Improvements in Typographical Distributing Machines, of which the following is a specification.

This invention relates to typographical 10 machines, such as linotype machines of the general organization represented in U. S. Letters Patent to O. Mergenthaler, No. 4,36,532, wherein circulating matrices are released from a magazine in the order in 15 which they are to appear in print and then assembled in line, the composed line transferred to the face of a mold, the mold filled with molten metal to form a slug or linotype against the matrices which produce the 20 type characters thereon, and the matrices thereafter returned through a distributing mechanism to the magazine from which they started. In some machines, such as the commercial model 9, where matrices may be 25 drawn from several magazines and mixed together in the same line, the distributing mechanism includes a primary distributor, which first sorts the matrices according to font, and a plurality of main distributors 30 which sort the matrices of the individual fonts according to character and restore them to their proper channels in the magazines. With this type of distributing mechanism, the matrices, after font separation, 35 pass down chutes or tubes and enter so-called lower distributor boxes, from which they are fed one at a time to the main distributors under the control of reciprocating pawls or escapements. In order that these 40 pawls or escapements may cooperate properly with the matrices, the latter are provided in their bottom edges with central notches, which necessarily vary in shape and depth according to the thickness of the 45 individual matrices.

Besides adding to the cost of production, such notches in the matrices materially limit the space ordinarily required for the regular font notches and moreover 50 seriously weaken the matrices, especially when the latter are formed with other necessary cuts or notches. Furthermore, matrices comprising fonts used on other machines, such as those of the single dis-

tributor class, are excluded from use on machines of the multiple distributor class described, since they do not have the required central notches. 55

The present invention is intended to obviate the foregoing difficulties and contemplates certain improvements whereby the distributing mechanism may receive and handle matrices of all fonts and this without the necessity for the objectionable central notches referred to. Accordingly, in 60 the preferred embodiment illustrated, each lower distributor box, instead of being provided with a pair of reciprocating pawls or escapements, as customary, is equipped with a matrix lifting finger and an associated 65 matrix pusher member, the former acting to feed the matrices one at a time to the overlying main distributor, and the latter acting to advance the matrices in proper order into the range of action of the lifting finger. 70

Similar arrangements have heretofore been proposed (see the Girod Patent No. 625,972 and the Grohmann Patent No. 759,969), but none has proved to be practical or satisfactory. In these prior instances, the pusher members were constructed to engage the bodies of the matrices, which vary widely in thickness, and hence the pusher members required too great a throw for practical 80 purposes. Moreover, these pusher members could not be relied upon to control the passage of the matrices through the distributor box or to advance them in proper upright position into operative relation to the lifting 85 finger and the other parts. Thus, when the pusher members were made to engage the matrices at their lower ends only, the matrices would almost inevitably assume an inclined position in their advance toward the 90 lifting finger and thus become wedged in the box, with the evil results which necessarily follow. Or, when the pusher members were made to engage the matrices more symmetrically, they would then in their forward 95 position arrest the matrices passing into the box at such a high level as to create a jam or else not afford time enough for the matrices to drop in front of the pusher members when in their retracted position. 100

According to the present invention, the pusher members are so constructed that the matrices will unfailingly be presented in 105

proper upright position to the lifting finger and at the same time allowed to pass through the distributor box with the necessary speed and facility. In addition, the construction of the pusher members is such that their throw or stroke may be reduced to a minimum and brought well within practical limits. Generally speaking, the pusher members are constructed and arranged to cooperate only with the projecting ears of the matrices, which feature, as will later be seen, brings about the improved results above noted.

In the accompanying drawings, the invention has been shown merely in preferred form and by way of example and as applied to the specific type of distributing mechanism indicated. However, many changes and variations may be made therein and in its mode of application, which will still be comprised within its spirit. It is to be understood, therefore, that the invention is not limited to any specific form or embodiment except in so far as such limitations are specified in the claims.

Referring to the drawings:

Fig. 1 is an elevation, showing part of a multiple distributor with the present improvements applied thereto;

Fig. 2 is an elevation, partly broken away, of the improved distributor box;

Fig. 3 is a horizontal section taken on the line 3—3 of Fig. 2;

Fig. 4 is a vertical section taken through the distributor box;

Fig. 5 is an end view thereof, partly in section;

Figs. 6 and 7 are detail sections, showing the operation of the pusher member;

Fig. 8 is a detail perspective of a portion of the distributor box with its matrix guide block detached;

Fig. 9 is a perspective view of the matrix pusher member detached;

Fig. 10 is a detail perspective showing the manner of supporting a thick matrix immediately prior to its engagement with the distributor bar; and

Fig. 11 is a detail transverse section, showing the means for operating the pusher member and lifting finger.

Referring to Fig. 1, the matrices X are dropped by the primary distributor A into tubes or chutes A¹ and enter one or another of the lower distributor boxes B, through which they are guided in upright position by their projecting ears x upon the upper and lower inclined rails B¹. The rails of each box are extended beneath the receiving end of the corresponding main distributor, the latter comprising as usual the longitudinally ribbed bar C and the set of matrix conveying screws C¹. The foregoing parts and their mode of operation, except as hereinafter pointed out, are or

may be of any approved construction or as embodied in the commercial model 9 linotype.

In carrying out the present invention, each of the lower distributor boxes B is equipped with a reciprocating matrix pusher member D and a matrix lifting finger E, the pusher member D being constructed and arranged to engage the matrices by their projecting ears x and acting to deliver them forwardly in a vertical position, without danger of tilting or displacement, to a point where they are engaged by the finger E and lifted thereby into the threads of the distributor screws C¹. The pusher member D (Figs. 2, 4 and 11) is slidably mounted in the base plate B¹¹ of the distributor box B and is loosely connected near its outer end to the lower end of a bell crank lever F pivoted at F¹ to the distributor box. The lever F is moved in one direction (inwardly) by a spring F² and in the opposite direction by a cam F³ carried on a shaft F⁴, the latter receiving motion from one of the distributor screws C¹. The shaft F⁴ is also provided with a cam F⁵, which controls the operation of the matrix lifting finger E through the spring-rod E¹, the rocking lever E², and the return spring E³. The finger E and pusher D are thus operated in perfect synchronism in feeding the matrices to the distributor.

Angular bracket plates D¹ (Fig. 9), fastened near the inner end of the member D and rising from opposite sides thereof, extend forwardly and carry a pair of blocks D² arranged to engage the upper ears of the matrices. Corresponding blocks D³, arranged to engage the lower ears of the matrices, are formed by recessing or bifurcating the end of the member D. As thus constructed, the pusher member is adapted to engage the matrices by all four ears and hence is capable of advancing them in perfect upright position.

The rails B¹ (see particularly Fig. 8) are formed with matrix arresting shoulders B², which rise from horizontally disposed portions B³. The rails are further formed with upwardly inclined and horizontal portions B⁴ and B⁵, which serve to support the matrices after they have been lifted above the shoulders B² and until they engage the distributor bar C.

A separator blade G, which is customarily used in connection with a lifting finger, is also provided. In the present instance, however, besides performing its normal function of keeping succeeding matrices in place while the leading one is being lifted, it prevents the forward tilting or displacement of a matrix while supported by the pusher blocks D² as the latter move toward the shoulders B². The upper rails B¹ are made wide enough in rear of the lifting fin-

ger E to engage the lower ears of a matrix and keep it from swinging forwardly during the simultaneous movement of the pusher blocks D³.

- 5 In the operation of the parts, the pusher blocks D² and D³ move in suitable slots horizontally across the inclined portions of the upper and lower rails B¹, the upper horizontal edges of said blocks being made of 10 such extent that the matrices will be checked thereby except when the pusher member occupies its retracted position. In this position of the pusher member, the course of a matrix is unobstructed and it is free to pass 15 by the pusher blocks and drop onto the horizontally disposed portions B³ of the rails (see Fig. 7). At other times, however, the matrices will be arrested by the engagement of their projecting ears with the horizontal 20 edges of the pusher blocks, as indicated in the case of the matrix shown at the right in Fig. 6, the stroke of the blocks being such that the number of matrices released thereby is perfectly controlled. When the 25 matrices are released and drop onto the horizontally disposed portions B³ of the rails, they are immediately subjected to the action of the pusher blocks and are advanced thereby, without danger of tilting or displacement, solidly and squarely up against the arresting shoulders B² (see dotted lines, Fig. 7). At this point, they are lifted by the finger E clear of said shoulders and into the 30 threads of the conveying screws C¹, as indicated by the matrix at the left in Fig. 6. The screws then advance the matrices along the inclined and horizontal portions B⁴ and B⁵ of the rail extensions into engagement 35 with the distributor bar C.
- 40 As well understood in the art, the projecting ears x of the matrices are of substantially uniform thickness throughout the matrices of all fonts, and hence the throw or stroke of the pusher member may be reduced to a minimum. Moreover, since the 45 matrix ears are located at the four corners of the matrices and in the same vertical plane, the advance of the matrices by the engagement of the pusher member with such 50 projecting ears will necessarily result in the presentation of the matrices in perfect upright position between the lifting finger E and the overlying separator blade G, it being understood that the matrix arresting 55 shoulders B² (like the matrix ears) are located in the same vertical plane. Furthermore, inasmuch as the pusher blocks D² and D³ are adapted to engage only with the projecting ears of the matrices, the latter are 60 allowed to pass downwardly through the distributor box until arrested by the engagement of their projecting ears with said pusher blocks (the matrix body portions being unobstructed), and hence when the pusher blocks are withdrawn, the matrices are 65

obliged to fall a very short distance in dropping onto the horizontally disposed portions B³ of the distributor box rails, having ample time to make this drop before the pusher blocks are moved forwardly again to advance them into the range of action of the lifting finger.

The horizontal portions B⁵ of the lower rail extensions are preferably arranged to extend beneath the body of a matrix rather than its lower projecting ears, as shown in Figs. 7 and 10. The point is that, in the case of very thick matrices, the tooth combinations and projecting ears (located at opposite sides thereof) are so widely separated that the tooth combinations would fail to engage the distributor bar before the projecting ears had passed beyond the rail extensions unless some such means of support were provided.

Having thus described my invention, its construction and mode of operation, what I claim and desire to secure by Letters Patent of the United States, is as follows:

1. In a typographical distributing machine equipped with matrices formed with projecting ears, the combination of a matrix distributor, a reciprocating finger for delivering the matrices successively to the distributor, and means to cooperate with the ears of the matrices for advancing the latter into the range of action of said reciprocating finger.

2. In a typographical distributing machine equipped with matrices formed with projecting ears, the combination of a matrix distributor, a matrix lifting finger associated therewith, and a cooperating matrix pusher member having ear engaging portions, substantially as and for the purpose described.

3. In a typographical distributing machine equipped with matrices formed with projecting ears, the combination of a primary distributor, a plurality of main distributors, distributor boxes arranged to cooperate with the main distributors, matrix lifting fingers associated with said distributor boxes, and matrix pusher members also associated with the distributor boxes and having portions to engage the matrices by their projecting ears.

4. In a typographical distributing machine equipped with matrices formed with projecting ears, the combination of a distributor box through which matrices gravitate for distribution, a matrix lifting finger associated therewith, and a cooperating pusher member having portions to engage the matrices by their projecting ears.

5. In a typographical distributing machine equipped with matrices formed with projecting ears, the combination of a distributor box provided with internal rails having inclined portions upon which matrices are

guided by their projecting ears as they pass therethrough, a matrix lifting finger associated therewith, and a matrix pusher member operating horizontally across said 5 inclined rail portions and having portions to engage the matrices by their projecting ears.

6. In a typographical distributing machine equipped with matrices formed with projecting ears, the combination of a distributor box through which the matrices gravitate for distribution, a matrix lifting finger associated therewith, a matrix separator blade located above and in operative relation to 10 the lifting finger, and means to cooperate with the projecting ears of the matrices for advancing them into the range of action of the lifting finger.

7. In a typographical distributing machine 20 equipped with matrices formed with projecting ears, the combination of a distributor box through which the matrices gravitate for distribution, and provided with internal rails having inclined portions, horizontal 25 portions and terminal matrix arresting shoulders to cooperate with the projecting ears of the matrices, a matrix lifting finger associated therewith, and a reciprocating pusher member acting to advance the 30 matrices supported by the horizontal rail portions up against the arresting shoulders and over the lifting finger, the said pusher member being formed with portions to engage the matrices by their projecting ears.

35. 8. In a typographical distributing machine equipped with matrices formed with projecting ears, the combination of a distributor box through which matrices gravitate for distribution, a matrix lifting finger associated therewith, and a reciprocating pusher member provided with block portions to engage the matrices by their projecting ears, the said block portions serving in the forward position of the pusher member to arrest or retard the matrices in their 40 passage through the distributor box.

9. In a typographical distributing machine equipped with matrices formed with projecting ears, the combination of a distributor box through which matrices gravitate for distribution, a periodically operated matrix lifting finger associated therewith, and a reciprocating pusher member operated in synchronism with the lifting finger, and 45 provided with block portions to engage the matrices by their projecting ears.

10. In a typographical distributing machine equipped with matrices, each formed at its four corners with projecting ears, the 50 combination of a matrix distributor, a periodically operated finger for feeding the matrices successively to the distributor, and a matrix pusher member operated in synchronism with the finger and provided with 55 four engaging portions arranged in posi-

tion to engage the matrices by all four projecting ears, substantially as shown and described.

11. In a typographical distributing machine equipped with matrices, each formed at its four corners with projecting ears, the combination of a matrix distributor, a periodically operated finger for feeding the matrices successively to the distributor, and associated means to cooperate with all four 70 projecting ears of the matrices for advancing the latter into the range of action of the finger.

12. In a typographical distributing machine, the combination of a matrix distributor comprising a distributor bar and a set of conveying screws, means for feeding matrices one at a time into the threads of the distributor screws, and means for guiding the matrices during their advance by the 80 screws onto the distributor bar, the said guiding means including a supporting track arranged to maintain engagement with the body portion of the matrices until the latter become supported by the distributor bar.

13. In a typographical distributing machine equipped with matrices formed with projecting ears, the combination of a distributor box through which the matrices gravitate for distribution, a matrix lifting finger associated therewith, and a reciprocating pusher member for advancing the matrices into the range of action of the lifting finger, the said pusher member being constructed to cooperate with the projecting 90 ears of the matrices in controlling the passage of the latter through the distributor box.

14. In a typographical distributing machine equipped with matrices formed with projecting ears, the combination of a distributor box through which the matrices gravitate for distribution, and means cooperating with the projecting ears of the matrices for controlling the passage of the latter through the distributor box.

15. In a typographical distributing machine equipped with matrices formed with projecting ears, the combination of a distributor box through which the matrices gravitate for distribution and provided with internal rails for guiding the matrices by their projecting ears, and a reciprocating member controlling the passage of the matrices along the rails and provided with block portions to cooperate with the projecting ears of the matrices in exercising such control.

16. In a typographical distributing machine equipped with matrices formed with projecting ears, the combination of a distributor box through which the matrices gravitate for distribution and provided with internal rails for guiding the matrices by their projecting ears, the said rails pre-

senting downwardly inclined portions and horizontally disposed portions and with horizontal slots separating the inclined from the horizontally disposed portions, and a reciprocating member controlling the passage of the matrices down the inclined rail portions and provided with block portions movable in said horizontal slots to cooperate with the projecting ears of the matrices in permitting the latter to drop onto the horizontally disposed rail portions.

17. In a typographical distributing machine equipped with matrices formed with projecting ears, the combination of a distributor box through which the matrices gravitate for distribution, a matrix lifting finger associated therewith, and a reciprocating pusher member constructed to engage

the matrices at all four corners in advancing said matrices into the range of action of the lifting finger.

18. In a typographical distributing machine equipped with matrices formed with projecting ears, the combination of a distributor box through which the matrices gravitate for distribution, a matrix lifting finger associated therewith, and means cooperating with the projecting ears of the matrices and acting at one time to arrest the matrices in their passage through the distributor box and at another time to advance said matrices into the range of action of the lifting finger.

In testimony whereof, I have affixed my signature hereto.

JOHN R. ROGERS.
